(57) **CLAIM**

The ornamental design for a “show stand,” for tiles and ceramic products, as shown and described.

DESCRIPTION

FIG. 1 is a perspective view of the show stand for tiles and ceramic products showing our new design;

FIG. 2 is a top plan view thereof;

FIG. 3 is a bottom plan view thereof;

FIG. 4 is a front view thereof;

FIG. 5 is a right side view thereof;

FIG. 6 is a left side view thereof; and,

FIG. 7 is a perspective view (in an open configuration) thereof.

The broken lines shown in FIG. 7 are for illustrative purposes only and form no part of the claimed design.
